UNITED STATES PATENT OFFICE.

FRANK HUBER, OF MIDDLETON, INDIANA.

CAN-ASSORTING DEVICE.

Application filed March 20, 1926. Serial No. 96,211.

This invention relates to a can separating or assorting device, and has for its object to provide, in a manner as hereinafter set forth, a machine of such class for separating or assorting cans of larger from cans of smaller diameter and for conducting off the cans of larger diameter in a runway independent of the runway for conducting off the separated or assorted cans of smaller diameter.

10 A further object of the invention is to provide, in a manner as hereinafter set forth, a machine for the purpose referred to with means controlled by the cans of larger diameter to prevent them from passing into the 15 runway employed for conducting off the separated cans of smaller diameter.

Further objects of the invention are to provide, in a manner as hereinafter set forth, a can separating or assorting machine which 20 is simple in its construction and arrangement, strong, durable, compact, thoroughly efficient in its use, automatic in its operation, readily assembled and comparatively inexpensive to manufacture.

25 With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

30 In the drawings wherein like reference characters denote corresponding parts throughout the several views:—

Figure 1 is a side elevation of a can separating and assorting machine, in accordance 35 with this invention.

Figure 2 is a top plan view thereof.

Figure 3 is a longitudinal section of the machine and further illustrating in dotted lines the cans of smaller diameter separated 40 from a can of larger diameter.

Figure 4 is an elevation of the machine looking toward the front end thereof.

Figure 5 is a vertical sectional view of the machine and further illustrating in full 45 and dotted lines respectively the controlling means in normal and in active position to prevent the entrance of cans of larger diameter into the runway for the cans of smaller diameter.

Figure 6 is a perspective view of the body portion of the machine.

Figure 7 is a perspective view of one of the sections of the controlling means to prevent the entrance of the cans of larger diameter into the runway for the cans of smaller 60 diameter.

A can separating and assorting machine, in accordance with this invention, includes a body portion, best shown in Figure 6 and which comprises a pair of oppositely dis-

posed angle-shaped bars referred to generally by the reference characters 1, 2 and disposed at a downward inclination in a direction towards the front of the body portion. Each of said bars consists of a rear portion 70

3, a forward portion 4 and an intermediate portion 5. The rear portion 3 consists of a vertically disposed leg 6 and a horizontally disposed leg 7 which extends inwardly from the bottom of the leg 6. The forward portion 75

4 comprises a vertically disposed leg 8 and a horizontally disposed leg 9 which extends inwardly with respect to the bottom of the leg 8. The intermediate portion 5 consists solely of a vertical leg 10 which is 80

of less height than the leg 6, or the leg 8 and has its top edge flush with the top edges of the legs 6 and 8. The bottom edge of the leg 10 is spaced a substantial distance above the horizontal legs 7 and 8 and forms a passage 11 for a purpose to be presently referred to. The rear portion 3 of the bars 1 and 2 85

provide a runway A which is common to the cans of larger and smaller diameters. The forward portion 4 of the bars 1 and 2 90

provides a runway B for the cans of larger diameter. The inner ends of the leg 7 are spaced a substantial distance from the inner 95

ends of the leg 9 to form a passage 12 for a purpose to be presently referred to. The inner ends of the legs 7 are connected together by a flat transversely extending combined coupling and bracing member 13 which 100

is positioned against the lower faces of said legs 7 and secured thereto by the hold-fast devices 14. The rear ends of the legs 7 are connected together by a flat transversely extending combined coupling and bracing member 15 which is positioned against the 105

lower faces of said legs and secured therewith by the hold-fast devices 16. The inner ends of the legs 6 are formed with spaced openings 16 for a purpose to be presently referred to. The inner ends of the legs 8 are provided with spaced openings 17 for 110

a purpose to be presently referred to. Secured to the outer face of each of the legs 8, 115

at the forward end thereof, is a downwardly extending hanger bar 18 which has its forward edge flush with the forward end edge of a bar 1 or 2.

5 Arranged below the intermediate portions of the bars 1 and 2 are a pair of angle bars, which are oppositely disposed with respect to each other and are indicated generally by the reference characters 19 and 20. The bar 10 19 is positioned below the bar 1 and the bar 20 is positioned below the bar 2. The bar 19 as well as the bar 20 has the rear terminal portion thereof curving upwardly as at 21 and which extends in close proximity to the 15 member 18 and has its top edge substantially in alignment with the forward edge of said member 18. The forward end of the bars 19 and 20 are flush with the forward side edges of the hangers 18 and one of the hangers 20 18 is secured to the outer face of the bar 19, as at 22 and the other hanger 18 is secured to the outer face of the bar 20 as at 23. The bar 19, as well as the bar 20 includes a vertically extending leg 24 and a horizontally extending leg 25 which projects inwardly from the bottom of the leg 24. The legs 25 of the bars 19 and 20 are secured together in proximity to their forward ends by a transversely extending combined coupling and brace member 26, which is secured against the lower faces of the said legs 25. The bars 19 and 20 provide a runway C for the separated cans of smaller diameter.

35 The body portion is supported at an inclination by two pair of vertically disposed supporting standards. The standards of one pair are indicated at 27, 28 and the standards of the other pair at 29, 30. The standards of each pair are arranged in spaced relation 40 and oppose each other. The standards of the said pairs are of the same height. Each standard of each pair is formed of an angle iron consisting of a pair of legs 31 and 32 disposed at right angles with respect to each 45 other. The legs 31 extend transversely with respect to the body of the machine and the legs 32 extend longitudinally with respect to the body of the machine. The legs 31 of each pair of standards oppose each other 50 and the legs 32 of one pair of standards oppose the legs 32 of the other pair of standards. The standards 27 and 29 are the forward standards and the standards 28 and 30 are the rear standards. The standards of 55 each pair are oppositely disposed with respect to each other, that is to say the leg 32 of one standard of a pair projects rearwardly and the leg 32 of the other standard of a pair projects forwardly. Extending through the legs 32 of the standard 8 are hold-fast devices 33 which also project through the openings 16 in the bar 2 and provides means for securing said bar 2 to the standard 28. The openings 16 in the bar 1 are provided 60 for the passage of hold-fast devices which

extend through the leg 32 of the standard 30 and provide means for securing the bar 1 to the standard 30. Extending through the leg 32 of the standard 27 and through the opening 17 in the bar 2 are hold-fast devices 34 for securing the bar 2 to the standard 27. The openings 17 in the bar 2 are provided for the passage of hold-fast devices which extend through the leg 32 of the standard 29 for the purpose of securing the bar 1 to the said standard 29. The hold-fast devices which extend through the leg 32 of the standard 28 are indicated at 35 and the hold-fast devices which extend through the leg 32 of the standard 29 are indicated at 36. Hold-fast devices 37 extend through the leg 32 of the standard 27 and through the bar 20 for connecting the latter to the said standard 27. Hold-fast devices 38 extend through the leg 32 of the standard 29 and through the bar 19 for the purpose of connecting the latter to said standard 29. The legs 31 of the standard 37 has secured thereto a pair of pivot rods 39, 40, the former is arranged near the upper end of the leg 31 of the standard 27 and the latter near the lower end of said leg. The pivot rods 39 and 40 are also connected to the legs 31 of the standard 28. The leg 31 of the standard 29 has connected thereto a pair of pivot rods 41, 42, the former arranged near the top of the leg 32 and the latter near the lower end thereof, and said pivot rods 41 and 42 are connected to the leg 32 of the standard 30. A pair of washers are mounted on each pivot rod in proximity to the ends thereof and said washers are indicated at 43, 44.

90 Mounted on the pivot rods 39 and 40 are respectively yokes 43, 44 which are oppositely disposed with respect to each other and the former has its arms 46, 47 project inwardly and outwardly with respect to the standards 27 and 28. The yoke 44 has its arms 48 and 49 project inwardly and outwardly with respect to the standards 29 and 30. The arms of the yoke 43 swing on the pivot rod 39 and the arms of the yoke 44 swing on the pivot rod 41. The washers on the pivot rods 39 and 41 are arranged between the arms of the yoke and the legs 31 of the standard.

100 Positioned against the inner side of the base of the yoke 43 is a shifting arm 49 and positioned against the inner face of the base of the yoke 44 is a shifting arm 50. The arms 49 and 50 are arranged in spaced relation and extend lengthwise with respect to the body portion. The arms 49 and 50 are of the same length and of a length to project rearwardly and forwardly with respect to the pairs of supporting standards. The arm 49 is constructed in the same manner as the arm 50 and but one of which will be described, as the description of one will apply to the other, and each of said arms comprises 110 115 120 125 130

a forward portion 50' having a rounded forward edge 51, and a tapered rear portion 52, which extends rearwardly with respect to the standards 28 and 30. Each arm is formed with a pair of vertically disposed spaced slots 53 and through which extend hold-fast devices 54 for connecting the arm to its respective yoke. Each hold-fast device consists of a headed bolt provided with a winged nut.

The arm 46 of the yoke 43 terminates at its outer end in a depending arm 55 having an inwardly curved lower terminal portion 57. The arm 48 of the yoke 44 at its outer end terminates in a depending arm 56 provided with an inwardly curved lower terminal portion 57. Mounted on the pivot rod 40 is a pair of spaced vertically extending bars 58, 59 provided at their upper ends respectively with inwardly extending flanges 60, 61. The bar 58 is of greater length than the bar 59 and depends below the lower end of the latter. Positioned on the flanges 60, 61 is a rectangular closure plate 62 for one of the passages 12 or the passage 12 formed intermediate the bar 2. The plate 62 is formed with spaced transversely extending slots and projecting through the flanges 60, 61 and slots 63 are hold-fast devices 64 for connecting the plate 62 to the upper ends of the bars 58 and 59. Each of said hold-fast devices consists of a headed bolt provided with a winged nut and with the head of the bolt countersunk in a slot 63. The bar 58 and its flange 60 is formed with a vertical slot 65 through which extends a pivot 66 carried by the curved lower terminal portion 56 of the arm 55 and which sets up a connection between the bar 49 and the yoke 43 for a purpose to be presently referred to. Mounted on the pivot rod 42 is a pair of vertically disposed bars 67, 68 provided respectively at their upper ends with inwardly extending flanges 69, 70. The arm 67 is of greater length than the arm 68 and depends below the lower end of the latter. Mounted on the flanges 69, 70 is a rectangular closure plate 71 provided with a pair of spaced transversely extending slots 72 through which extends hold-fast devices 73 for connecting the plates 71 to the flanges 69 and 70. Each hold-fast device consists of a headed bolt and a winged nut and with the head of the bolt countersunk in a slot 72. The arm 67 in proximity to its flange 69 is formed with a vertical slot 74 through which extends a pivot 75 carried by the lower terminal portion 57 of the arm 56 and by such arrangement a connection is had between the bar 67 and the yoke 44 for a purpose to be presently referred to. The bar 58 is connected to the bar 68 by a coiled spring 76 which normally acts to maintain the closure plates 62 and 71 in the full line position shown in Figure 5 whereby the passages 12 are normally open.

The plates 62 and 71 are swung to closure position with respect to the passages 12 through the openings or passages 11 and the manner in which said plates are swung to closure position will be presently referred to.

The controlling means which prevents the cans of larger diameter from falling into the runway for the cans of smaller diameter consists of two oppositely extending spring controlled elements. One of said elements is formed by the arm 49 and the connecting devices therebetween and the pivot rods 39 and 40 and the other of said elements is formed by the arm 50 and the connecting devices therebetween with the pivot rods 41, 42. The arms 49 and 50 are positioned in the path of the cans of larger diameter whereby the cans as they move down the runway A will engage and shift the arms 49 and 50 and rock the spring controlled elements against the action of their controlling springs and the rocking movement of said elements will be towards each other so that the plates 62 and 71 will close the passages 12 and act as a support for cans of larger diameter and form bridges so that the cans of larger diameter will pass from the runway A onto the runway B and further be prevented from dropping onto the runway C. The normal position of the controlling means is as shown in Figure 5 of the drawings, that is say in full lines whereby the closure plates 62 and 71 will be positioned outwardly with respect to the passages 12 or rather clear of said passages 12 so that as a can of smaller diameter rolls off the runway A it will pass through the passages 12 into the runway B. The cans of smaller diameter do not impact against the arms 49 and 50. The cans of larger diameter impact against the arms 49 and 50 before they reach the inner end of the runway A so that the controlling means will be actuated and shifted to the dotted line position shown in Figure 5, whereby the plates 62 and 71 will close the passages 12, and as the cans of larger diameter leave the runway A they will pass over the closure plates and onto the runway B.

Secured to the rear portions of the lower faces of the legs 8, of the runway B, as well as projecting rearwardly of said legs 8, is a cushioning element 77, formed from a rectangular pad of resilient material. The element 77 prevents the can from impacting against the rear end edges of the legs 8 as it drops through the opening, and thereby prevents the denting of the cans.

The outer ends of the runways B and C may be provided with conductors for the separated cans and one of said conductors is indicated at 78 and is positioned with respect to the runway B. The conductors form no part of the invention.

The machine provides a simple and expe-

ditious means for separating and assorting cans of one diameter with respect to the other, or in other words for separating cans of larger diameter from cans of smaller diameter, and therefore it is thought that a machine for such purpose, in accordance with this invention, owing to its simplicity in construction provides a cheap and meritorious device for the function referred to, and although the preferred embodiment of the invention is as illustrated and described, yet it is to be understood that changes in the details of construction can be had which will fall within the scope of the invention as claimed.

What I claim is:—

1. A machine for the purpose set forth comprising a primary runway for conducting cans of different diameters to be separated, an upper runway for conducting off the separated cans of larger diameter, a lower runway for conducting off the separated cans of smaller diameter, said upper runway having its inner end spaced from the inner end of the primary runway to provide an opening for the passage of the cans of smaller diameter onto the lower runway as such cans pass off the primary runway, and means operated by the cans of larger diameter travelling on the primary runway for bridging said opening to prevent such cans from passing into the lower runway and for conducting such cans to the upper runway for discharge.

2. A machine for the purpose set forth comprising a primary runway for conducting cans of different diameters to be separated, an upper runway for conducting off the separated cans of larger diameter, a lower runway for conducting off the separated cans of smaller diameter, said upper runway having its inner ends spaced from the inner end of the primary runway to provide an opening for the passage of the cans of smaller diameter onto the lower runway as such cans pass off the primary runway, means operated by the cans of larger diameter travelling on the primary runway for bridging said opening to prevent such cans from passing into the lower runway and for conducting such cans to the upper runway for discharge, and said means including a controlling spring for normally maintaining it clear of said opening.

3. A machine for the purpose set forth comprising a primary runway for conducting cans of different diameters to be separated, an upper runway for conducting off the separated cans of larger diameter, a lower runway for conducting off the separated cans of smaller diameter, said upper runway having its inner end spaced from the inner end of the primary runway to provide an opening for the passage of the cans of smaller diameter onto the lower runway

as such cans pass off the primary runway, means operated by the cans of larger diameter travelling on the primary runway for bridging said opening to prevent such cans from passing into the lower runway and for conducting such cans to the upper runway for discharge, said means including a pair of pivotally supported shifting arms arranged in the path of and operated by the cans of larger diameter, shiftable closure plates for bridging said opening, and a controlling spring for normally maintaining said plates in non-bridging position.

4. A machine for the purpose set forth comprising a primary runway for conducting cans of different diameters to be separated, an upper runway for conducting off the separated cans of larger diameter, a lower runway for conducting off the separated cans of smaller diameter, said upper runway having its inner end spaced from the inner ends of the primary runway to provide an opening for the passage of the cans of smaller diameter onto the lower runway as such cans pass off the primary runway, means operated by the cans of larger diameter travelling on the primary runway for bridging said opening to prevent such cans from passing into the lower runway and for conducting such cans to the upper runway for discharge, said means including a pair of pivotally supported shifting arms arranged in the path of and operated by the cans of larger diameter, shiftable closure plates for bridging said opening, a controlling spring for normally maintaining said plates in non-bridging position, and said arms extending over said primary runway and having tapered rear ends engaged by the cans of larger diameter.

5. A machine for the purpose set forth comprising a primary runway for conducting cans of different diameter to be separated, an upper runway for conducting off the separated cans of larger diameter, a lower runway for conducting off the separated cans of smaller diameter, said upper runway having its inner end spaced from the inner end of the primary runway to provide an opening for the passage of the cans of smaller diameter onto the lower runway as such cans pass off the primary runway, means operated by the cans of larger diameter travelling on the primary runway for bridging said opening to prevent such cans from passing into the lower runway and for conducting such cans to the upper runway for discharge, and said lower runway having an upstanding curved can receiving end extended to a point in close proximity to said opening.

6. A machine for the purpose set forth comprising a primary runway for conducting cans of different diameter to be separated, an upper runway for conducting off

- the separated cans of larger diameter, a lower runway for conducting off the separated cans of smaller diameter, said upper runway having its inner end spaced from 5 the inner end of the primary runway to provide an opening for the passage of the cans of smaller diameter onto the lower runway, as such cans pass off the primary runway, means operated by the cans of larger diameter 10 travelling on the primary runway for bridging said opening to prevent such cans from passing into the lower runway and for conducting such cans to the upper runway for discharge, said means including a controlling spring for normally maintaining it clear of said opening, and said lower runway having an upstanding curved can receiving end extended to a point in close proximity to said opening.
- 15 7. A machine for the purpose set forth comprising a runway for conducting off separated cans of larger diameter, a runway for conducting off separated cans of smaller diameter, and means at the inner ends of
- 20 said runways and operated by the cans of larger diameter to prevent these latter from passing into the runway for conducting off the cans of smaller diameter and for directing the cans of larger diameter onto their respective runway.
- 25 8. A machine for the purpose set forth comprising a runway for conducting off separated cans of larger diameter, a runway for conducting off separated cans of smaller diameter, means at the inner ends of said runways and operated by the cans of larger diameter to prevent these latter from passing into the runway for conducting off the cans of smaller diameter and for directing the cans of larger diameter onto their respective runway, and said means including a controlling element for maintaining it in non-directing position until operated by the cans of larger diameter.
- 30 35 40 45 In testimony whereof, I affix my signature hereto.

FRANK HUBER.
